DESIGN FOR A PARKING METER DEVICE

Carl C. Magee, Oklahoma City, Okla., assignor to
Dual Parking Meter Company, Oklahoma City,
Okla., a corporation of Delaware

Application December 6, 1935, Serial No. 59,940

Term of patent 14 years

To all whom it may concern:

Be it known that I, Carl C. Magee, a citizen of the United States, residing at Oklahoma City, in the county of Oklahoma and State of Oklahoma, have invented a new, original, and ornamental Design for Parking Meter Devices, of which the following is a specification, reference being had to the accompanying drawing, forming a part thereof.

Figure 1 is an oblique elevational view of the front and right-hand faces of the device; and,

Figure 2 is a view similar to Figure 1, but showing opposite faces of the device.

I claim:

The ornamental design for a parking meter device, as shown.

CARL C. MAGEE.
